GOLF CLUB HEAD

Ivan M. Meissler, Providence, R.I. (18 Olympic Village, Apt. 1/C, Chicago Heights, Ill. 60411)

Filed Mar. 25, 1974, Ser. No. 454,673

Term of patent 14 years

Int. Cl. D21—02

U.S. Cl. D34—5 GH

FIG. 1 is a front elevational view of a golf club head showing my new design;

FIG. 2 is a right end elevational view thereof;

FIG. 3 is a rear elevational view thereof;

FIG. 4 is a left end elevational view thereof;

FIG. 5 is a top plan view thereof;

FIG. 6 is a bottom plan view thereof;

FIG. 7 is a section taken on line 7—7 of FIG. 3;

FIG. 8 is a section taken on line 8—8 of FIG. 3;

FIG. 9 is a section taken on line 9—9 of FIG. 3; and

FIG. 10 is a section taken on line 10—10 of FIG. 3.

I claim:

The ornamental design for a golf club head, substantially as shown.
